UNITED STATES PATENT OFFICE.

ANTHONY ANIA, OF CORONA, NEW YORK.

AEROPLANE.

1,312,300.

Specification of Letters Patent.

Patented Aug. 5, 1919.

Application filed February 28, 1919. Serial No. 279,704.

To all whom it may concern:

Be it known that I, ANTHONY ANIA, a subject of the King of Italy, residing at Corona, in the county of Queens and State 5 of New York, have invented new and useful Improvements in Aeroplanes, of which the following is a specification.

This invention relates to new and useful improvements in aeroplanes, and has for its 10 primary object to provide a means by which the landing of a machine from a flight may be facilitated.

A further object of the invention is to provide a device of this character which 15 will effectively right the machine and cause the same to assume a proper horizontal position in landing.

A further object of the invention is to provide a device of this character in which 20 the shocks and jars incident to landing of aeroplanes is entirely eliminated.

The device is an improvement over the device shown in Patent No. 1,285,893, granted to me, and is adapted to use equally well 25 in connection with aeroplanes of all types.

Referring to the drawings:—

Figure 1 is a side view of a portion of an aeroplane showing the device in place thereon.

Fig. 2 is a front elevation of a portion of 30 an aeroplane partly in section.

Fig. 3 is a detail sectional view.

Fig. 4 is a horizontal sectional view.

Referring more particularly to the drawings, the reference character 5 designates 35 the fuselage of an aeroplane, which is preferably of the biplane type, the upper and lower planes being designated by the reference characters 6 and 7 respectively.

Mounted between the upper and lower 40 planes 6 and 7 are two tubular members 8, the upper end of each of which is closed as at 9, the lower end of each of these tubular members being open and adapted to register 45 with its respective opening 10 in the lower plane 7.

The reference character 11 designates the traction wheels of the device, and said 50 wheels are mounted on the opposite ends of the axle 12. Projecting upwardly from said axle 12 in spaced relation are two rigid rods 13, these rods being long enough to extend into the tubular members 8 with their upper ends 14 arranged in spaced relation with the 55 upper closed end 9 of the tubes 8.

Located beneath the lower plane 7, and

secured to the under face thereof is a buffer member 15 which is provided with two spaced openings 16 adapted to register with the spaced openings in the lower plane 7 and 60 the open lower end of the tubes 8.

Surrounding each of the rigid members 13 is a coil spring 17 the lower end of which is adapted to engage the axle 12, the upper end of each of said springs engaging the 65 under face of the buffer plate 15. Mounted between the upper end of each of the rigid members 13 and the closed end 9 of the tubular members 8 is a coil spring 18 which is adapted at times to compression under the 70 action of engagement of the traction wheels 11 with the ground when landing.

By this construction, it is apparent that the body or fuselage and the planes are 75 resiliently mounted with respect to the traction wheels and that all shocks and jars attendant the landing of the machine are readily taken up and effectively absorbed.

Connected to the axle 12 intermediate of its ends is a forwardly extended member, 80 and to the forward end of this member 20 as at 21 is a ground engaging shoe or the like 22 the outer end of which is curved upwardly and rearwardly as at 23.

Extending downwardly and forwardly 85 from the buffer plate 15 is an arcuate tubular guide member 24, this member 24 being secured to the buffer plate 15 by means of bolts 26.

Secured to the ground shoe 22 on the upper 90 face thereof, and conforming in curve to, and projecting into the arcuate guide member 24 is a rigid member 25. Between the free inner end 26 of the rigid member 25, and the base of the arcuate tubular guide 95 member 24 is a coil spring 27.

The operation of the device is as follows:—

In landing, the ground shoe 22 first engages the ground, the shock being absorbed 100 or taken up by the coil spring 27. When the ground shoe 22 engages the ground surface there is a tendency to cause the machine to assume a horizontal plane, in which position the traction wheels 11 engage the 105 ground.

By the arrangement of springs herein shown it will be apparent that all of the shocks and jars incident to the landing of an aeroplane are obviated, thus materially 110 reducing the dangers usually attending this operation.

Having thus described the invention, what is claimed is:—

1. In an aeroplane, a pair of traction wheels, an axle for said wheels, uprights connected with said axle, tubular members receiving the ends of said uprights, springs in said tubular members engaging the ends of the uprights and shock absorber springs through which the uprights pass below the 10 tubular members and located between the axle and a stationary part of the device.
2. In an aeroplane, a pair of traction

wheels, an axle for said wheels, a shoe pivotally mounted to the axle and having a forwardly extending part, the end of said forwardly extending part being curved upwardly, a curved upright on said shoe, a curved tubular member on the lower part of the aeroplane receiving said curved upright and a spring in the tubular member engaging the end of the curved upright.

In testimony whereof I have affixed my signature.

ANTHONY ANIA.
